UNITED STATES PATENT OFFICE

BRUNO C. METZNER, OF NEW YORK, N. Y.

DESIGN FOR AN ASTRONOMICAL STAR-DOME

Application filed October 15, 1932. Serial No. 45,370. Term of patent 7 years.

To all whom it may concern:

Be it known that I, BRUNO C. METZNER, a citizen of the German Reich, residing at New York, in the county of New York and State of New York, have invented a new, original, and ornamental Design for an Astronomical Star-Dome, of which the following is a specification, reference being had to the accompanying drawing, forming part thereof.

Fig. 1 is an elevation of the astronomical star-dome, showing my new design, and Fig. 2 is an inner view of the same.

I claim:

The ornamental design for an astronomical star-dome, as shown.

BRUNO C. METZNER.
